Specification for Design.

Patented Nov. 23, 1920.

Application filed March 20, 1920. Serial No. 367,489. Term of patent 7 years.

To all whom it may concern:

Be it known that I, MORRIS OZLEK, a citizen of the United States, residing at Philadelphia, in the county of Philadelphia and States of Pennsylvania, have invented a new, original, and ornamental Design for a Cluster-Top for Lamps, of which the following is a specification, reference being had to the accompanying drawing, forming a part thereof, in which—

Figure 1 is a front elevational view of a cluster top for lamps showing my improved design,

Fig. 2 is a top plan view of the cluster top shown in Fig. 1,

Fig. 3 is a side elevation of Fig. 2, and

Fig. 4 is a section taken on the line 4—4 of Fig. 3.

I claim:

The ornamental design for a cluster top for lamps, as shown.

MORRIS OZLEK.
